CLAIM

The ornamental design for the flexible pouch, as shown and described.

DESCRIPTION

FIG. 1 is a perspective view of the front of a pouch of the present invention which includes two shaped cutouts; FIG. 2 is an elevational view of the front of the embodiment of the invention depicted in FIG. 1; FIG. 3 is a plan view of the top of the embodiment of the invention depicted in FIG. 1; FIG. 4 is an elevational view of the rear of the embodiment of the invention depicted in FIG. 1; FIG. 5 is a plan view of the bottom of the embodiment of the invention depicted in FIG. 1; FIG. 6 is an elevational view of the left of the embodiment of the invention depicted in FIG. 1; and, FIG. 7 is an elevational view of the right of the embodiment of the invention depicted in FIG. 1. The broken lines in FIGS. 1, 2, and 4 are for illustrative purposes only and forms no part of the claimed design.
